UNITED STATES PATENT OFFICE.

JOHN H. DEPPELER, OF WEEHAWKEN, NEW JERSEY, ASSIGNOR TO METAL & THERMIT CORPORATION, OF CHROME, NEW JERSEY, A CORPORATION OF NEW JERSEY.

CRUCIBLE FOR ALUMINO-THERMIC REACTIONS FOR WELDING OPERATIONS.

Application filed April 10, 1923. Serial No. 631,157.

To all whom it may concern:

Be it known that I, JOHN H. DEPPELER, a citizen of the United States, and a resident of Weehawken, in the county of Hudson and State of New Jersey, have invented certain new and useful Improvements in Crucibles for Alumino-Thermic Reactions for Welding Operations; and I do hereby declare the following to be a full, clear, and exact description of the invention, such as will enable others skilled in the art to which it appertains to make and use the same.

The invention relates to crucibles employed primarily in carrying out alumino-thermic reactions for welding operations, and has for its object to construct a crucible of such form as will ensure the quiet and uniform propagation of the reaction after the latter has been initiated. Heretofore, it has been the custom to employ crucibles of relatively long, narrow, conical construction, on the assumption that such a form of crucible was necessary in view of the fact that reaction of an alumino-thermic mass proceeds downwardly with great rapidity, and very slowly in a lateral direction. The expedient of providing a relatively deep, narrow body of thermit in the conical crucible was followed on the assumption that only by such an arrangement could a rapid melting of the body of metal in the crucible be effected. It has been found, however, that the reaction is so violent, when carried out in such a body, that a considerable portion of the slag is erupted or thrown out of the crucible with danger to the operator, and also to the impairment of the ultimate product, which is liable to contain some slag. For example, it has been found that if a thermit mixture were ignited in a vertical pipe, the reaction would be extremely violent, blowing most of the contents out of the pipe, whereas if the same amount of the mixture were laid on a flat plate, the reaction would be propagated very slowly, if at all. It is highly desirable, of course, to secure a quiet and complete reaction between the thermit and the metal to be melted, and at the same time to ensure the development and retention of the maximum heat within the mass until the superheated molten metal is discharged from the crucible. In welding operations, it is important that the reaction should be rapid enough to melt the steel quickly so that it will retain its superheat,

but it is also important that the reaction should be quiet, so that the steel will quickly separate from the slag, and may be readily tapped from the crucible after the reaction, instead of continuing the reaction for some time attended by a more or less violent ebullition of the melting material, which, as indicated, will render the steel of an inferior quality, and cause an admixture of the slag therewith, unless great care is taken.

The present invention contemplates the provision of a crucible of such form that the reaction will be propagated quietly and with uniformity throughout the mass, thus eliminating the danger of spattering the contents, as well as the loss of material, and at the same time producing an excellent high quality thermit steel free from slag and entrapped gases. Such a crucible is shown in the accompanying drawing, in which the figure represents the crucible in sectional elevation.

Referring to the drawing, it will be noted that the crucible comprises a body of refractory material generally circular in cross section with the sides 1 inclined inwardly to a slight degree from the vertical, and merging into a relatively broad, concave bottom 2, which is provided with a central tapping outlet 3, which latter is equipped with the usual refractory tubular stone 4, in which is applied the removable and replaceable tapering thimble 5. It has been found that if the crucible be made so that the maximum diameter is substantially equal to the height, so that the mass of the material to effect the alumino-thermic reaction within the crucible is comparatively wide at all transverse sections taken at right angles to the vertical axis of the crucible, the reaction when initiated at the surface will proceed downwardly and laterally throughout the mass, quietly and uniformly, without any tendency to throw any of the molten material out of the crucible, and the molten metal will quickly settle and separate from the slag, which latter will float on top of the molten metal, when the latter can be discharged from the bottom opening without danger of any admixture of slag therewith.

While the crucible constituting the instant invention has been described as having a maximum diameter substantially equal to the height of the vessel, it will be understood that these dimensions may be varied

within reasonable limits without departing from the invention, so long as the crucible is constructed with a relatively broad bottom and with a diameter approximately equal to 5 the height.

What I claim is:
A crucible for effecting alumino-thermic reactions for welding operations, compris-

ing a shell of refractory material having a broad concave bottom provided with a 10 central pouring opening, the maximum diameter of the shell being substantially equal to the height of the same.

In testimony whereof I affix my signature.

JOHN H. DEPPELER.
